UNITED STATES PATENT OFFICE.

DANIEL J. BUTTERFIELD, OF LOS ANGELES, CALIFORNIA.

DESIGN FOR CASING FOR A GUM-VENDING MACHINE.

Application filed November 28, 1922. Serial No. 4,433. Term of patent 14 years.

To all whom it may concern:

Be it known that I, DANIEL J. BUTTERFIELD, a citizen of the United States, residing at Los Angeles, in the county of Los Angeles and State of California, have invented a new, original, and ornamental Design of a Casing for a Gum-Vending Machine, of which the following is a specification, reference being had therein to the accompanying drawing.

In the drawing:

The figure is a perspective view of a casing for a gum vending machine, showing my new design.

What I claim is:

The ornamental design for a casing for a gum vending machine, as shown.

In testimony whereof I hereunto affix my signature.

DANIEL J. BUTTERFIELD.
